(57) **CLAIM**

The ornamental design for a hand piece switch adaptor, as shown and described.

DESCRIPTION

FIG. 1 depicts a perspective view of embodiment 1 of a hand piece switch adaptor, showing our new design;

FIG. 2 depicts a top view of the design of FIG. 1;

FIG. 3 depicts a side view of the design of FIG. 1;

FIG. 4 depicts a bottom view of the design of FIG. 1;

FIG. 5 depicts a front view of the design of FIG. 1;

FIG. 6 depicts a back view of the design of FIG. 1;

FIG. 7 depicts a perspective view of embodiment 2 of a hand piece switch adaptor, showing our new design;

FIG. 8 depicts a top view of the design of FIG. 7;

FIG. 9 depicts a side view of the design of FIG. 7;

FIG. 10 depicts a bottom view of the design of FIG. 7;

FIG. 11 depicts a front view of the design of FIG. 7; and,

FIG. 12 depicts a back view of the design of FIG. 7.
